UNITED STATES PATENT OFFICE.

FRANK D. WINKLEY, OF MADISON, WISCONSIN.

WINDMILL.

SPECIFICATION forming part of Letters Patent No. 391,571, dated October 23, 1888.

Application filed April 17, 1886. Serial No. 199,266. (No model.)

To all whom it may concern:

Be it known that I, FRANK D. WINKLEY, a citizen of the United States, residing at Madison, in the county of Dane and State of Wisconsin, have invented certain new and useful improvements in Windmills; and I do hereby declare the following to be a full, clear, and exact description of the invention, such as will enable others skilled in the art to which it pertains to make and use the same.

My invention relates to vertical sectional self-governing wind-wheels; and it consists, first, in the peculiar construction of the frame-work of the wheel, by which I attain a maximum of strength and durability with the minimum of materials.

My invention relates, further, to a vertical wind-wheel constructed in such a manner that the wind-wheel arms are subjected to compression strains only, the strains in lines parallel to the wheel's axis and those in lines perpendicular to the same being opposed, and counteracted by stay-rods supporting said wheel-arms, and arranged as hereinafter described.

It consists, further, in a certain arrangement of the parts, hereinafter to be described, by which the speed of the wind-wheel is regulated automatically.

Figure 1 is a side view, also partly in section, showing the wind-wheel shaft with its connections and one of the vane-sections thrown out of gear. Fig. 2 is a top view of Fig. 1 without the vane-section and its accompanying frame-work. Fig. 3 is an end view of Fig. 1, showing the wind-wheel out of gear, a portion of the vanes being cut away by passing a plane through the line xx of Fig. 4. Fig. 4 is a plan view of one of the wind-wheel sections in gear. Fig. 5 is a rear view of the governing-wheel, the opposite or front view of which is shown in Fig. 3. Fig. 6 is a detail showing the method of connecting the governing-rod to the vane sections.

In the drawings similar letters, where they occur, refer to like parts throughout the several views.

A is the tower-casting, adapted to be secured in the usual way to the tower-timbers. (Not shown in the drawings.)

B is a pivot shell or casting adapted to revolve inside the tower-casting A, the side-

thrust at the top of the shell being taken up by anti-friction rollers *a*, journaled to upright pins extending from the rim *b*. The pivot-shell is secured against any accidental vertical vibration by the collar *c* at the outer lower end of the tower-casting and secured to the lower extension of the pivot shell by a setscrew. (See Fig. 1.) The upper part of the pivot shell or casting is extended into a horizontal hollow arm, *C*, and supports the wheel-shaft *D*, at the inner end of which is the crank-disk *d*, attached by means of a crank-pin to the connecting-rod *E*, which is similarly connected at its lower end with a hollow plunger, *F*, through the center of which passes the regulating-wire *e*, connecting the chain *f* with the elbow-lever *G*, all that part of the mechanism just described being protected from the weather by the box-like shield *H*. The elbow-lever *G* is pivoted to an ear extending from the pivot-shell *B*, and supports at its outer end a weight, *W*, in the manner that such appliances are ordinarily attached in this class of mills.

To an upward extension of the lever *G*, I pivot, by means of the bolt *i*, the cross-bar *g*, at the outer ends of which are secured the rods *h h*, engaging with ears extending from opposite sides of the sliding collar *I*. The collar *I* is provided at its outer end with a recessed head or inclosing-rim, which engages over a corresponding circular rim on the inner end of the sleeve *K*, by which means the latter may be moved back and forth over the hollow arm *C* with the sliding collar *I*, at the same time being adapted to revolve freely about the wheel-shaft. The rods *J J*, pivoted to ears on opposite sides of the sleeve *K*, extend forward in a vertical plane parallel with the wheel-shaft *D*, and engage with angle-levers cast as a part of the sector-gears *M* and *N*. These sector-gears are journaled on arms extending at right angles from opposite sides of the collar *L*, which is secured to the wheel-shaft *D*.

The governing-wheel *J* is journaled on the outer end of the wheel-shaft *D*, the bearing being preferably smaller than the full size of the wheel-shaft proper, said wheel *J* being adapted to rotate freely on the same. When the vane-sections are in gear forming a continuous disk or wheel at right angles to the wheel-

shaft, the relative position of the governing-
5 rods R, in operative connection with the spokes
of the governing-wheel J, is shown by the dotted
lines, Figs. 3 and 5. If the wheel J were
10 to rotate farther than the limit thus shown by
the dotted lines referred to, the tendency would
be for the vane-sections to dish outward from
15 the plane of the wheel-disk, to which they are
normally confined. The governing-wheel J
20 is held to this limit as follows: The forward
or outer end of the collar L, rigidly secured
25 to the drive-shaft, as hereinbefore described,
is slotted (see Fig. 1) through a portion of its
30 circumference. The rear face of the hub of
the governing-wheel rotates freely over the
35 forward end of the collar L, and is provided
with a clutch or lug, which extends into said
40 slot in the front face of the collar L. When
45 the vane sections are closed in gear, said lug
50 strikes against the shoulder of said slot at the
instant the vane-sections close into a continuous
disk at right angles to the wheel-shaft,
55 thereby limiting the motion of the vane-sections
in this direction and preventing them
60 from dishing outward. When the vane-sections
65 are thrown out parallel to the wheel-
70 shaft, they are held to this position and lim-
ited as to further motion in this direction by
75 the governing-rod R, which in this position
80 are radial to the center of the governing-wheel
85 J, being a radial continuation of the spokes
90 of the same, to which they are respectively at-
tached. (See Fig. 1.) It is obvious that if
95 any further rotation of the governing-wheel
100 in this direction were possible it would sim-
ply result in drawing the respective vane-sections
105 in again; so for this purpose the lug need
not necessarily be arranged to strike the op-
posite limit of the slot. I prefer to accom-
110 plish this result by means of the govern-
115 ing-rod R in the connection described. The
120 clutch arrangement just described is a well-
125 known mechanical device, and I make no
130 claim to this particular feature as being new
and patentable. This limit is reached when
135 the vane-sections stand out parallel to the
140 drive-shaft D. At the same instant that this
145 limit is reached the governing-rod R respect-
150 ively assume the position radial to the center,
155 as shown in Figs. 1 and 3.

The number of radial spokes in the govern-
160 ing-wheel J will be determined by the number
165 of vane-sections in the wind-wheel. The inner
170 or rear face of this hub is provided with suit-
175 able sector-gears on opposite sides of the wheel-
180 shaft adapted to mesh into and operate with
185 the sector-gears M and N, respectively. By
190 the disposition of the sector-gearing on oppo-
195 site sides of the wheel-shaft, as described, one
200 set of gears supplements and assists the action
205 of the other, thus doing away with any cramp-
210 ing or jamming of the parts and securing quick
215 and responsive action in the governing device.
220 The hub, radial spokes, and sector-gears of
225 the governing-wheel I prefer to make together
230 in a single casting.

The wind-wheel hub proper, P, and the disk-

hub O are united by a sleeve, preferably in a
single casting, and keyed to the wheel-shaft D.
The drive-pin p, extending through the periph-
70 ery of the disk-hub O and the sleeve K, com-
municates to the latter the rotary motion of
75 the wheel-shaft. The preferably radial spokes
80 k of the wind-wheel are made, preferably, of
gas-piping, which I prefer to screw into the
85 wheel-hub P, as shown in Fig. 1, and are
90 braced by the stay-rods l, bolted at their outer
95 ends to tips n screwed on the outer ends of said
spokes, and at their inner ends to the disk-hub
100 O. The point of connection of each of the
105 stay-rods l with the disk-hub O, instead of be-
ing in the radial plane passing through the
110 shaft D and the corresponding spoke k, is at
one side of said radial plane and on a line ap-
proximately at right angles thereto. The stay-
115 rod therefore lies wholly in a plane parallel to
the shaft D and approximately tangent to the
120 circular disk-hub at the point of attachment
of the stay-rod thereto. By means of this con-
struction the stay-rod braces the spoke of the
125 wind-wheel not only against wind-pressure
130 parallel to the wind-wheel shaft, but also
against strains resulting from any resistance
135 to the rotation of the wheel-shaft. The wind-
140 power applied to the rotation of the wheel-
145 shaft is transmitted to it through the spokes
150 k, and as any resistance to such rotation must
155 be overcome by rotary pressure on the spokes
160 it is evidently an advantage to brace them
165 against rotary strains as well as against strains
170 in the line of the shaft. Heretofore each of
175 the stay-rods of a wind-wheel frame has been
180 in the same plane with reference to the wheel-
185 shaft as the corresponding spoke, and has con-
190sequently offered no resistance to rotary strains
195 on the frame. My present construction over-
200 comes this defect and greatly strengthens the
205 frame without increasing the amount of mate-
210 rial employed therein. The spokes k are fur-
215 ther secured at their outer ends by the tie-rods
220 m, bolted through eyes in the tips n. The wind-
225 vanes o are permanently mortised into wooden
230 cross-pieces, the vanes of each section con-
235 verging toward the center, so that when in
240 gear they form one continuous flat disk. The
245 cross-piece or swivel-bar Q is provided with
250 a suitable casting secured to each end thereof,
255 each of said castings terminating in a pin,
260 which extends into a suitable opening in each
265 of the tips referred to, and is secured in posi-
270 tion by tightening up the tie-rod m. The
275 swivel-bar Q is so adjusted with reference to
280 the vane-section as to divide the latter into
285 two equal areas for receiving the wind-press-
290 ure. The inner cross-bar, T, is made extra
295 heavy in order to facilitate the automatic regu-
300 lation of the wind-wheel by employing the cen-
305 trifugal motion for throwing out the vane-sec-
310 tions when the wheel revolves beyond a certain
315 rate of speed.

The governing-rod R is attached to an eye
320 in the outer end of one of the short radial spokes
325 of the governing-wheel J, and is swiveled by
330 means of an adjustable link-connection at its

outer end to an ear or lug extending from a radial cross-bar, V, preferably of metal, which is firmly secured to the cross-pieces T and Q on the same side thereof as the vanes o. This 5 radial bar V is made, preferably, rather flat and elliptical in cross-section, its flat face between the points of attachment on the cross-pieces T and Q standing parallel with and between the adjacent vanes o, so as to impede as little as 10 possible the action of the wind on the vanes. The link-connection at the outer end of the governing-rod R is loosely swiveled over the ear on the radial bar V, in order to allow sufficiently free play of the jaws of said link to 15 prevent any cramping or binding of these parts at any point of the machine's operation, either in gear or out of gear.

The tie-rods m are bolted through suitable eyes in the tips n and unite the outer ends of 20 the spokes k, thus forming the containing-rim of the wind-wheel. By dishing the spokes k outward I am enabled to stay them much more securely than if they stood at right angles to the wheel-shaft, for while the stay-rods l are 25 just as effective in preventing the spokes k, thus dished, from being forced outward by the wind-pressure, the tie-rods m serve also as stay-rods to prevent the spokes from being forced inward and backward or "wrong side out" by 30 any sudden change in the direction of the wind, as may often happen, for it is obvious that if the spokes k were to be thus forced backward toward or into a plane at right angles to the wheel-shaft the outer ends of the 35 spokes k must spread farther apart, and it is by resisting this tendency that the tie-rods m perform the double function of a rim holding the vane-sections together, also of stay-rods to resist any backward wind-pressure. If the 40 spokes k were inserted in the hub P at right angles to the wheel-shaft, the tie-rods m could not, for obvious reasons, perform this added function of supplemental stay-rods against backward pressure.

45 It is evident that the improvement resulting from the novel arrangement of the stay-rods hereinbefore described is wholly independent of the dishing of the spokes. If the spokes were set at right angles to the wheel-shaft, so 50 as to lie in a single plane, the placing of the stay-rods in planes diverging from the radial planes of the respective spokes would be as advantageous as in the structure shown and described, and I do not intend, therefore, to 55 limit my invention in that respect to any special arrangement of the spokes with reference to the shaft.

The description just given of one of the vane sections and the adjacent parts is similar 60 in all respects to that of the other five sections, (not shown in the drawings;) but I do not restrict myself to any particular number of sections in the wind-wheel.

65 The disk-hub O, hub P, and their connecting-sleeve, the spokes k, set in the hub, the stay-rods l, and the tie-rods m form a single permanent rigid structure whose parts are al-

ways in the same relative positions. No one of these parts has any function whatever in the regulation of the mill, and, in fact, the entire wheel-frame coacts with the other parts of the mill precisely as if it were formed from a single piece of metal or of a series of pieces riveted together.

The wind-wheel operates on the leeward side 75 of the tower, turning about the latter with the pivot-shell B, according to the direction of the wind.

Having described the construction of my machine, I will now explain how it operates. 80 When the machine is in gear, the vane-sections together form a flat disk in a vertical plane at right angles to the direction of the wheel-shaft. As the wind increases, the speed of the revolving wind-wheel also increases, until the 85 centrifugal force begins to open the inner ends of the vane-sections toward the tower and against the wind, the swivel-bar Q turning on its pivots journaled in the spoke-tips n. At the instant the vane-sections begin to "dish" 90 or open inward this motion is communicated to the governing-rods R, which revolve the governing-wheel J in the direction indicated by the arrow, Fig. 1. This motion, continuing, reaches its limit when the vane-sections have 95 opened inward through an angle of about ninety degrees, when the governing-rods will be in the position shown in Figs. 1 and 3, the original position of the same and the arc through which the governing-wheel turns being shown by the broken lines in Figs. 3 and 5. The governing-wheel J, revolving through the arc indicated, communicates its motion 100 through the sector-gearing to the rods j j and h h, raising the weight W to the position shown in Fig. 1, further motion in this direction being limited by the clutches or lugs on the collar L and governing-wheel J, respectively, engaging, as shown in Fig. 2. The angular motion 105 of the weight W in this operation is shown by the broken line, Fig. 1. It is obvious that in Fig. 1, further motion in this direction being limited by the clutches or lugs on the collar L and governing-wheel J, respectively, engaging, as shown in Fig. 2. The angular motion 110 of the weight W in this operation is shown by the broken line, Fig. 1. It is obvious that when the force of the wind abates so that it no longer equals the opposing force of the weight W the latter will fall to its first position, reversing the operation of throwing the 115 vane-sections out of the wind, as just described, and bringing them back into gear in the form of a plane disk, as before. In this position the cross-piece T of the vane-section bears against the governing-rod R. The wire e, attached to 120 the chain f, enables the operator to throw the machine in or out of gear at will.

What I claim, and desire to secure by Letters Patent of the United States, is—

1. The combination, with a wind-wheel shaft, 125 of a wheel-hub and a circular disk-hub rigidly connected and mounted thereon, a series of radial spokes set in said wheel-hub, and a corresponding series of stay-rods, each having its outer end fastened to the outer end of one of 130 said spokes and its inner end fastened to the periphery of said disk-hub, said stay-rod lying wholly in a plane parallel to the wheel-shaft and approximately tangent to the disk-hub at

the point of attachment of the rod thereto, and being inclined with reference to the plane of the spoke and shaft in the direction of the wind's rotary force upon the wheel, substantially as and for the purpose set forth.

2. The combination, with a wind-wheel shaft, of a wheel-hub and a disk-hub rigidly connected and mounted thereon, a series of radial spokes set in said wheel-hub and dished outwardly and away from the normal wind-pressure, a corresponding series of tie-rods connecting the outer ends of said spokes, and a corresponding series of stay-rods, each having its outer end fastened to the outer end of one of said spokes and its inner end fastened to the periphery of said disk-hub, and lying wholly in a plane parallel to the wind-wheel shaft and approximately tangent to the disk-hub at the point of attachment of the stay-rod thereto.

3. In a windmill of the class described, as an automatic governing device, the weight W, attached to the elbow-lever G, pivoted to the shell B, in combination with the wheel-shaft D, cross bar g, rods h h, collar I, sleeve K, rods j j, sector-gears M N, governing-wheel J, governing-rods R, and the series of vane-sections adapted to rotate on their respective swivel-bars Q, journaled in the spoke-tips n,

the inner end of each of said vane-sections being weighted, whereby the automatic regulation of the wind-wheel is facilitated, all as set forth, and for the uses and purposes mentioned.

4. In a windmill of the class described, the collar L, rigidly secured to the shaft D, and provided with arms extending at right angles from opposite sides of the same, in combination with the sector-gears M and N, respectively provided with angle-levers standing at right angles to said arms and on opposite sides of the same, and the governing-wheel J, provided on its inner hub-face with corresponding gears operatively connected with said gears M and N, whereby the weight W and the respective vane-sections are made to operate reciprocally on each other, thereby co-operating to govern the machine automatically, all as set forth.

In testimony whereof I have signed this specification in the presence of two subscribing witnesses.

FRANK D. WINKLEY.
